TABLE

Irving M. Rosen, White Plains, N.Y., assignor to The Pace Collection Inc., New York, N.Y.

Filed Jan. 24, 1973, Ser. No. 326,300

Term of patent 14 years

Int. Cl. D6—03

U.S. Cl. D6—177

FIG. 1 is a perspective view of a table according to the invention;

FIG. 2 is a plan view of the table;

FIG. 3 is a bottom view of the table; and

FIG. 4 is a side view of the table, the opposite side view being identical.

I claim:

The ornamental design for a table, as shown.
